[57] **CLAIM**

The ornamental design for a forehead cushion for face protective devices, as shown and described.

DESCRIPTION

FIG. 1 is a perspective view of a forehead cushion for face protective devices, showing my new design;
FIG. 2 is an enlarged section view taken on plane 2—2 in FIG. 1;

FIG. 3 is an unfolded side elevational view thereof;
FIG. 4 is an elevational view taken from the side opposite that shown in FIG. 3; and
FIG. 5 is an enlarged section view taken on plane 5—5 in FIG. 3.

FIG. 1

FIG. 2

FIG. 5

FIG. 3

FIG. 4
